(57) CLAIM

The ornamental design for a canopy for a pick-up truck, as shown and described.

DESCRIPTION

FIG. 1 is a top, rear, and left side perspective view of a canopy for pick-up truck embodying my new design as installed on an exemplary vehicle;

FIG. 2 is a top, rear, and left side perspective view of the canopy for pick-up truck as a standalone unit;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof; and

FIG. 8 is a bottom plan view thereof.

The parts shown by broken lines in the reproductions are not part of the claimed design.
